UNITED STATES PATENT OFFICE.

WALTER B. McCONNELL, OF PHILADELPHIA, PENNSYLVANIA.

INK-BOTTLE HOLDER.

1,417,081.

Specification of Letters Patent. Patented May 23, 1922.

Application filed June 8, 1921. Serial No. 476,048.

To all whom it may concern:

Be it known that I, WALTER B. McCONNELL, a citizen of the United States, residing at Philadelphia, in the county of Philadelphia and State of Pennsylvania, have invented new and useful Improvements in an Ink-Bottle Holder, of which the following is a specification.

My invention relates to new and useful improvements in an ink bottle holder, and has for its object to provide an exceedingly simple and effective device of this character that will be relatively inexpensive in the cost of manufacture.

Another object of the invention is to provide a holder of the class mentioned so that a bottle may be readily placed therein providing, in effect, an individual ink well which cannot be easily upset making it practical for use by small children of school age as well as larger children and adults.

A further object of the invention is to construct the ink bottle holder of two parts namely a base and body each having interlocking parts so that when a bottle is placed between them it will be held against accidental displacement, the base being of sufficient size to prevent the device from being tipped over when the upper portion thereof is accidentally touched by a person.

A still further object of the invention is to so form and combine the two parts as to produce pen holder rests in combination with the bottle holder.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is a perspective view of an ink bottle holder constructed in accordance with my invention showing an ink bottle therein.

Fig. 2, is a similar view of a slightly different formation with the bottle removed.

In carrying out my invention as here embodied, 2 represents the base of the holder which is preferably made of metal of sufficient size to give a large bearing surface upon a desk, table or other object and the

ends of this base are bent upon themselves to provide the overhanging or overlapping flanges 3 the end edges of which are spaced from the base for the insertion of 60 coacting parts of the body to be hereinafter described and these overlapping flanges are inclined outward and may be arcuate in cross section if so desired, the inclination thereof being for a purpose to be later explained. From the side edges of the base are formed the upturned or vertical side flanges 4 which extend between the overlapping flanges 3 on both sides of the base.

The reference numeral 5 denotes the body 70 consisting of a roof 6 having a hole 7 therethrough the side walls 8 which preferably diverge toward their lower ends and outwardly projecting flanges 9 formed from the lower ends of said side walls and adapted to underlie the inner or end edges of the overlapping flanges 3 when the two parts of the holder are placed together. The body is also preferably formed of sheet metal preferably having some resiliency so that 80 the lower ends of the side walls will always tend to spring outward and thus be securely held beneath the overlapping flanges and it is to be also noted that said walls should be of a width approximately equal to the 85 distance of the two upstanding flanges 4 so that said side walls will lie within said flanges, thus preventing the body from shifting sidewise.

When the body is in place upon the base 90 member the coaction of the side walls with the overlapping flanges 3 provide a pen holder rest at each end of the bottle holder the inclination with the overlapping flanges retaining the pen or pencil placed thereon 95 as will be obvious.

To place a bottle in the holder or remove one therefrom it is only necessary to take hold of the body and apply sufficient pressure to the side walls 8 to force them toward 100 each other which will withdraw or disengage the outwardly projecting flanges 9 on said side walls from the ends of the overlapping flanges 3 at which time the body may be lifted free from the base and a bottle such as is shown and designated by the numeral 10 may be lifted from the base, if to be removed, or one placed on said base and the body then placed thereover and the side walls 8 inserted between the upstanding flanges 4 at which time the neck of the bottle will protrude through the open-

ing 7, then by releasing the side walls 8 they will spring outward and cause the outwardly projecting flanges 9 to enter the spaces between the inner edges of the overlapping flanges and the base thereby interlocking the two parts of the holder.

As the body is connected with or attached to the bottle, by the projection of the neck of the latter through the hole in the roof of 10 the body any shifting of said body or the bottle will be limited by the upstanding flanges 4 thus preventing the accidental detachment of the body from the base, but where the side walls of the body are so bent 15 that they do not pass beyond the ends of the upstanding flanges when connected with the base, these upstanding flanges will prevent shifting of the body by direct coaction therewith.

20 In Fig. 2, I have shown a slightly different formation for the base although the body is exactly the same and in this form of the device the overlapping flanges 11 are so bent as to be parallel with the coacting 25 portions of the base, while from the inner ends of said flanges project the extensions 12 which overlie the overlapping flanges and with the side walls of the body produces pen holder rests.

30 If found desirable the ends of the base may be bent downward as plainly shown in Fig. 2 so that only the folded edges rest upon an object and act as feet for the bottle holder. In all other respects both forms 35 here illustrated are identical in construction.

From the foregoing description it will be particularly noted that I have produced an exceedingly simple and inexpensive bottle 40 holder particularly for small size bottles which latter may be readily placed therein or removed therefrom and when in place cannot be accidentally tipped over under ordinary circumstances.

45 Of course I do not wish to be limited to the exact details of construction as herein shown as these may be varied within the limits of the appended claims without departing from the spirit of my invention.

50 Having thus fully described my invention, what I claim as new and useful is:—

1. An ink bottle holder comprising a base having an overlapping flange at each end and a body including a roof having a hole therethrough, side walls and outwardly projecting flanges at their lower ends for coaction with the overlapping flanges.

2. An ink bottle holder consisting of a base and a body, said base having an overlapping flange at each end and said body in-

cluding side walls having an outward tension and provided with outwardly projecting flanges contacting with the overlapping flanges and normally held in engagement therewith by the outward tension of said side walls.

3. An ink bottle holder consisting of a base provided with an overlapping flange at each end and spaced from said base, an upstanding flange at each side of the base between the overlapping flanges and a body consisting of a roof having an opening therethrough, side walls formed integral with said roof and outwardly projecting flanges at the lower ends of said side walls, said last named flanges adapted to underlie said overlapping flanges.

4. An ink bottle holder consisting of a base provided with an overlapping flange at each end and spaced from said base, an upstanding flange at each side of the base between the overlapping flanges and a body consisting of a roof having an opening therethrough, side walls formed integral with said roof and outwardly projecting flanges at the lower ends of said side walls, said last named flanges adapted to underlie said overlapping flanges, said overlapping flanges being inclined outward and with the sides of the body forming a pen holder rest.

5. In a device of the character stated, a base member portions thereof being bent upon itself to form overlapping flanges, integral upstanding flanges formed with the side edges of said base, a body roof having an opening therethrough, integral side walls formed therewith, and integral outwardly projecting flanges formed with the lower ends of said side walls and interlocking with the overlapping flanges to attach the body to the base.

6. In a device of the character stated, a base member portions thereof being bent upon itself to form overlapping flanges, outwardly inclined flange extensions formed with said overlapping flanges, said extensions overlying said flanges, integral upstanding flanges formed with the side edges of said base, a body roof having an opening therethrough, integral side walls formed therewith, integral outwardly projecting flanges formed with the lower ends of said side walls and interlocking with the overlapping flanges to attach the body to the base, said flange extensions coacting with the side walls to form a writing instrument rest.

In testimony whereof, I have hereunto affixed my signature.

WALTER B. McCONNELL.
